SPACING MECHANISM FOR PUNCHING MACHINES.

Application filed June 2, 1926. Serial No. 113,152.

This invention relates to feed mechanism for metal working machines, and more especially to a combined automatic and manually operated feed mechanism for advancing the work in the path of the machine where it is to be acted upon.

It is among the objects of this invention to provide a feed mechanism which shall be adapted to function automatically during the normal operation of the machine with which it is associated to feed the work or carrier on which it is supported in the path of the mechanism such as the dies of punch presses for acting upon the work, and which in addition thereto shall be provided with means for manually operating the feeding mechanism to adjust the work to its initial position and to take up the slack in the feed mechanism prior to the subsequent automatic operation of the machine.

Another object of this invention is to provide a feed mechanism of the above designated character which shall embody simple, efficient, and positive means for rotating the feed shaft automatically or manually to advance the work in the path of the machine and to positively secure the feed shaft or carrier in the position to which it is advanced.

Another object of this invention is to provide a feed mechanism which shall be adapted for automatic or manual operation, and in which the mechanism for effecting the automatic or manual operation shall be independently operative and in which a positive feed stop or retaining means shall be operative by either of the feeding mechanisms.

In accordance with the present invention a feed mechanism comprising a ratchet device and mounted or associated with a feed shaft operatively connected to a work carrier is provided with a plurality of pawls adapted to interact with the teeth of a ratchet wheel, one of said pawls being associated with the drive mechanism of a machine tool to adapt it to automatically feed the ratchet wheel during the operation of the machine. Another pawl is mounted through mechanical linkage to a hand lever by means of which it is actuated to act upon the ratchet wheel to operate the feeding mechanism, and a third pawl is adapted to engage the ratchet wheel to lock it in its advanced position by means of a fluid pressure actuating device

which is independently operated by the moving parts of the machine or manually actuated feeding elements.

This invention is particularly applicable to the feeding of sheet metal or punch presses, and particularly automatic punch presses in which the work is fed in the direction of the die and in which the feeding of the material is coordinated with the punching action of the die members. This type of machine is necessary to adjust the work with respect to the position of the dies to secure a proper alignment of the material with respect to the position of the die members and to take up all the slack or lost motion in the feed mechanism so as to secure an accurate spacing of the cuttings of the die in the initial strokes of the punching bar. It is therefore desirable to provide a feeding mechanism which may be manually operated to secure the initial adjustment and proper location of the sheet metal as described and to subsequently continue the feeding of the work automatically by connecting the feed mechanism with the drive member of the punch press.

In the accompanying drawings constituting a part hereof and in which like reference characters designate like parts, Fig. 1 is a side elevational view of a fragmentary portion of a punch press having a feed mechanism associated therewith embodying the principles of this invention; Fig. 2 is a cross sectional view taken along the lines II-II, Fig. 1, of a slotted link illustrated in the lower left hand corner of the machine shown in Fig. 1; Fig. 3 is a view partially in section and partially in elevation, of a fluid pressure control mechanism; Fig. 4 is a plan view of the movable elements of the mechanism shown in Fig. 3; Fig. 5 is a view partially in elevation and partially in cross section of a punch press and carrier, the latter being adapted to support and feed the sheet metal or work in the direction of the punch dies as will be hereinafter explained; and Fig. 6 is a cross sectional view taken along the line VI-VI, Fig. 1.

Referring to Figs. 1 and 2 of the drawing the structure therein illustrated comprises a punch press 1 having a rear frame portion in which a crank shaft 3 and a feed shaft 4 are journaled for rotation, the shaft 4 being provided with a gear wheel 5, Fig. 5, the teeth of which engage or mesh with the

teeth of a rack 6 designated the carrier for supporting and feeding sheet metal 7 which is fastened by clamp 8 mounted on the carrier 6 in the path of a plurality of punches 9 cooperating with die blocks 10. A lever arm 11, Fig. 1, is loosely mounted on the hub 12 of a ratchet wheel 13 that is secured to rotate with the feed shaft 4, and a bell crank 14 is similarly mounted on the ratchet wheel 13 or on the shaft 4.

A pawl 15 is pivoted at 16 on the swing frame 11, and is adapted to rest against a stop 17 provided thereon. The pawl 15 is connected by a link 18 to a floating lever 19 having a slotted link 20 pivoted thereon and having a connected rod 21 extending to the front of the punch press 1, and which is pivoted at 22 to a hand lever 23 provided with a stub 24 movable between the limits of the end portions of a segment bracket 25.

The link 20 is associated with the swing frame 11 in the manner shown in Fig. 2 by a bolt 26 extending through the slotted portion 27. A plurality of washers 28 having a coil spring 29 disposed around the bolt 26 and between the washers are secured in spaced relation by a nut 30 to provide a yielding brake to yieldingly restrain the movement of the swing frame 11.

The bell crank 14 is provided with a pawl 31 pivoted at 32 and adapted to engage the teeth of the ratchet wheel 13, and the other end of the bell crank is connected to a link 33 pivoted at 34 to the bell crank 14.

As shown in Figs. 1 and 6, a rocker frame 38 is provided with trunnions 41 and 42 the latter being secured to the frame 38 by a key 43 and rocks with it. The frame 38 is further provided with T-slots 44 and 45 of arcuate shape in which blocks 46 are slidably mounted. Links 47 are connected to blocks 46 at one end and slide bar 48 at the other end. A finger 49 is locked to the trunnion 42 by pin 49' to follow the motion of the frame 38 and a finger 50 is loosely pivoted on the trunnion 42. The link 33 is pivoted at 35 to the blocks 46.

As shown in Fig. 1, the slide bar 48 operates in a guide 51 of the frame 2 and extends therethrough. The end of the bar 48 is provided with a plate 52 that is movable between a pair of jaws 53 one of which is shown. The jaws are positively movable by a floating lever 54 connected to the frame 38 and their movement effect a corresponding movement of the plate 52 and its attached slide bar 48 which in turn adjusts the position of the blocks 46 to vary the throw of the link 33 and its cooperating ratchet pawl 31 in accordance with the movement of the rocker frame 38.

The finger 50, Figs. 1, 4 and 6 constitutes one arm of a crank lever the end 55 of which is pivoted at 56 to link 57 which is pivoted at 58 to lever 59 pivoted to the frame 2 at 60.

A link 61 is pivoted at its respective ends to the lever 59 at 60 and to the split bearing portion 62 of the swing frame 11 at 63.

Referring to Figs. 1, 3 and 4, the fingers 49 and 50 are movable between the projections 64 and 65 of a movable valve stem 66 mounted in a valve block 67, which is connected to a source of fluid pressure by a conduit 68 and which communicates by a conduit 69 with a cylinder 70, Fig. 1, having a movable plunger 71 for engaging a pawl 72, that is adapted to engage the teeth of the ratchet wheel 13. The pawl 72 is pivoted at 73 and is provided with an extension 74 that is disposed between a pair of friction plates 75 to steady its movement and to keep it in proper working alignment.

Referring to Fig. 3 the valve stem 66 is provided with packing rings 76 and 77 and is further provided with an intermediary constricted portion 78. The fluid pressure member 67 is provided with orifices 79 and 80 leading respectively to a source of fluid pressure and to the plunger cylinder 70. The packing rings 76 and 77 are in spaced relation and spaced apart to extend beyond the orifices 79 and 80 so that when they are in the position shown in Fig. 3 communication is established between the orifices thus establishing communication between the plunger conduit 69 and the conduit 68 leading to the pressure supply. When the packing ring 77 is moved to take the position between the orifices 79 and 80, the latter is cut off from the fluid pressure and is opened to the atmosphere.

The operation of the combined automatic and hand ratcheting mechanism is briefly as follows: In hand operation for ratcheting the work to adjust its position relative to the punches 9 the operator unlatches the hand lever 23 pulling it towards himself and effecting a corresponding movement of the rod 21 in the same direction. The link 18 and lever 19 will swing with the movement of the rod 21 with which they are connected causing pawl 15 to leave stop pin 17 and engage ratchet wheel 13. The swing arm 11 is held frictionally by the spring 29, Fig. 2, associated with the link 20. As the pawl cannot swing freely any more because of its engagement with the teeth of the ratchet wheel 13, any further movement of the hand lever 23 will cause ratchet wheel 13 and swing arm 11 to swing together overcoming friction of spring 29. This movement is limited by the bolt 26 engaging the end of the slot 27 in link 20.

The retaining pawl 72 during this operation will slip over the teeth in the ratchet wheel 13 and fall in to stop the ratchet wheel from retreating at the end of the stroke. At this point hand lever 23 is returned to its original position for a new stroke if necessary. When the ratchet wheel 13 and inci-

- dentally the material 7 has been advanced or adjusted the requisite amount, that is, has been brought to the proper starting point, lever 23 is pushed forward to its latched position as shown in Fig. 1 at which point the bolt 26 bottoms in slot 27, pawl 15 rests against the stop 17 and the system is locked up with the pawl 15 disengaged from ratchet wheel 13.
- 10 The retaining pawl 72 is operative for both hand and automatic operation of the ratcheting mechanism. For automatic operation the crank 40 is continuously revolving causing the rocker frame 38 to oscillate about its pivot 42 and produce a corresponding movement of the finger 49 which is keyed to trunnion 42 between the prongs 64 and 65 of the valve stem 66. In the path of movement of the rocker frame 38 the finger 49 will assume the position shown in Fig. 3 to move the packing rings 76 and 77 to establish communication between the orifices 79 and 80 thereby establishing pressure in the pipe line 69 communicating with the retaining pawl plunger 71 to engage the pawl 72 with the ratchet wheel 13. This retaining pawl actuating position of the finger 49 is established at the end of the stroke of the ratchet pawl 31 when the material to be punched has been adjusted to its new position and during the punching stroke of the machine the finger 49 is moved in the opposite direction to shift the valve stem 66 to establish communication of the pipe line 69 with the atmosphere thereby releasing the pawl retaining plunger 71 at the instant the ratcheting pawl 31 becomes operative. This cycle of operation continues during the automatic operation of the ratcheting mechanism.
- 40 When the punch is stopped, the valve stem 66 may be in the position where no pressure is on the plunger 71 to make the retaining pawl 72 operative for hand ratcheting. To provide for this condition the finger 50 constituting a part of the bell crank 55 is actuated by the linkage 57, 59 and 61 through the movement of the swing arm 11 in the initial stroke of the hand lever 23 to move the valve stem 66 to the position shown in Fig. 3 which is the position in which pressure is established in the plunger cylinder 70 forcing the retaining pawl 72 into engagement with the ratchet wheel 13. The pressure is maintained against the pawl 72 until the motion of the punch, when started, converts this system to automatic control.
- 60 The operation of the feed ratchet by the machine driven crank 40 and manually operated hand lever 23 are independent of each other and the actuation of the stop pawl 72 to hold the ratchet wheel 13 in its advanced position is independently effected by the manual or automatically operated ratcheting mechanism so as to readily permit the
- operation of the feed mechanism in either manner.
- It is evident from the foregoing description of this invention that a feed mechanism embodying the principles therein set forth is particularly applicable to the feeding of sheet metal into automatically fed punch presses for the purpose as herein set forth, and that the device is positive and accurate in its function of securing proper spacing of the work with respect to the punch dies and to take up lost motion in the movable parts of the feeding mechanism.
- Although several embodiments of this invention have been described, it will appear obvious to those skilled in the art that various modifications may be made in the details of construction and in the arrangement of the several cooperating parts without departing from the principles herein set forth.
- We claim:
1. In a punch press a feed mechanism comprising a work carrier adapted to advance the work in the path of the punch, actuating means for the carrier comprising a feed shaft operatively connected to said carrier, a ratchet mechanism carried by said shaft and adapted to intermittently rotate the same, means for automatically operating said ratchet mechanism, and manually operative means for said ratchet mechanism to advance the work carrier to a predetermined starting point.
  2. In a punch press a feed mechanism comprising a work carrier adapted to advance the work in the path of the punch, actuating means comprising a feed shaft operatively connected to said carrier, a ratchet mechanism carried by said shaft and adapted to intermittently rotate the same, a swing frame mounted on said mechanism, a ratcheting pawl carried by said frame, a link held in frictional engagement by said frame and a hand lever secured to said link for swinging said frame to effect engagement of said pawl with the ratchet mechanism and to advance said feed shaft.
  3. In a punch press a feed mechanism comprising a work carrier adapted to advance the work in the path of the punch, actuating means comprising a feed shaft operatively connected to said carrier, a ratchet mechanism carried by said shaft and adapted to intermittently rotate the same, a swing frame mounted on said mechanism, a ratcheting pawl carried by said frame, a link held in frictional engagement by said frame, a hand lever secured to said link for swinging said frame and to effect engagement of said pawl with the ratchet mechanism to advance said feed shaft, and means for securing said shaft in its advanced position.
  4. In a punch press a feed mechanism comprising a work carrier adapted to advance the material or work in the path of

the punch, means for automatically and manually actuating said carrier, and means for locking out of operative position said manually actuating means.

5. In a punch press a feed mechanism comprising a work carrier adapted to advance the material or work in the path of the punch, means comprising a ratcheting mechanism for actuating said carrier, means for automatically operating said mechanism, and means for manually operating the same, said automatic and manual operating means being independent of each other.

15. In a punch press a feed mechanism comprising a work carrier adapted to advance the material or work in the path of the punch, means comprising a ratcheting mechanism for actuating said carrier, means for automatically operating said mechanism, 20 means for manually operating the same, and means for rendering said last named means inoperative during the operation of said automatic means.

25. In a punch press a feed mechanism comprising a work carrier adapted to advance the work in the path of the punch, a feed shaft for actuating said carrier, a ratchet wheel mounted on said shaft, a pawl operative to automatically engage and rotate said wheel, a retaining pawl for engaging said wheel, means for holding said retaining pawl in engagement with said wheel, and means associated with said first named pawl to render said holding means operative.

35. In a punch press a feed mechanism comprising a work carrier adapted to advance the work in the path of the punch, a feed shaft for actuating said carrier, a ratchet wheel mounted on said shaft, a pawl operative to automatically engage and rotate said wheel, a retaining pawl for engaging said wheel, a fluid pressure system for holding said retaining pawl in engagement with said wheel, and means operative through said first named pawl to regulate said pressure system during the operation of said ratchet wheel.

45. In a punch press a feed mechanism comprising a work carrier adapted to advance the work in the path of the punch, a feed shaft for actuating said carrier, a ratchet wheel mounted on said shaft, a pawl operative to automatically engage and rotate said wheel, a second pawl adapted to engage and rotate said wheel, a manually operative mechanism for operating said last named pawl, a retaining pawl for engaging said wheel to lock the same in its advanced position, means for holding said retaining pawl in engagement with said wheel, and means for locking said manually operative mechanism during the automatic operation of said first named pawl.

55. In a punch press a feed mechanism comprising a work carrier adapted to ad-

vance the work in the path of the punch, a feed shaft for actuating said carrier, a ratchet wheel mounted on said shaft, a pawl operative to automatically engage and rotate said wheel, a second pawl adapted to engage and rotate said wheel, a manually operative mechanism for operating said last named pawl, a retaining pawl for engaging said wheel to lock the same in its advanced position, fluid pressure means for holding said retaining pawl in engagement with said wheel during the manual operation of the ratcheting mechanism, and means for intermittently engaging and disengaging said retaining pawl with said wheel during the automatic operation of said mechanism.

70. 11. In a punch press a feed mechanism comprising a work carrier adapted to advance the work in the path of the punch, a feed shaft for actuating said carrier, a ratchet wheel mounted on said shaft, a pawl operative to automatically engage and rotate said wheel, a second pawl adapted to engage and rotate said wheel, a manually operative mechanism for operating said last named pawl, a retaining pawl for engaging said wheel to lock the same in its advanced position, fluid pressure means for holding said retaining pawl in engagement with said wheel during the manual operation of the ratcheting mechanism, and means for releasing said fluid pressure when the automatically operative pawl is rendered operative.

75. 12. In a metal working machine a feed mechanism comprising a work carrier adapted to advance the work in the path of the machine, actuating means for said carrier comprising a feed shaft operatively connected to said carrier, a ratchet mechanism securely mounted on said shaft and adapted to intermittently rotate the same, means automatically operative through the drive mechanism of the machine to actuate said ratchet mechanism, and independent means for manually actuating said ratchet mechanism.

80. 13. In a metal working machine a feed mechanism comprising a work carrier adapted to advance the work in the path of the machine, actuating means for said carrier comprising a feed shaft operatively connected to said carrier, a ratchet mechanism securely mounted on said shaft and adapted to intermittently rotate the same, means automatically operative through the drive mechanism of the machine to actuate said ratchet mechanism, and means for manually actuating said ratchet mechanism while said automatic means is rendered inoperative.

85. 14. In a metal working machine a feed mechanism comprising a work carrier adapted to advance the work in the path of the machine, actuating means for said carrier comprising a feed shaft operatively con-

5 nected to said carrier, a ratchet mechanism securely mounted on said shaft and adapted to intermittently rotate the same, means automatically operative through the drive mechanism of the machine to actuate said ratchet mechanism, means for manually actuating said ratchet mechanism while said automatic means is rendered inoperative, and means for holding said feed shaft in its 10 advanced position during the intermittent operation of said ratchet mechanism.

15 15. In a metal working machine a feed mechanism comprising a work carrier adapted to advance the work in the path of the machine, actuating means for said carrier comprising a feed shaft operatively connected to said carrier, a ratchet mechanism securely mounted on said shaft and adapted to intermittently rotate the same, means 20 automatically operative through the drive mechanism of the machine to actuate said ratchet mechanism, means for manually actuating said ratchet mechanism while said automatic means is rendered inoperative, 25 and means for holding said feed shaft in its advanced position during the intermittent operation of said ratchet mechanism, said last named means being operatively connected to the said automatic and manual 30 actuating means.

16. In a metal working machine a feed mechanism comprising a work carrier adapted to advance the work in the path of the machine, actuating means for said carrier comprising a feed shaft operatively connected to said carrier, a ratchet mechanism securely mounted on said shaft and adapted to intermittently rotate the same, means automatically operative through the drive 35 mechanism of the machine to actuate said ratchet mechanism, means for manually actuating said ratchet mechanism while said automatic means is rendered inoperative, and a fluid pressure actuated device holding 40 said feed shaft in its advanced position during the intermittent operation of said ratchet mechanism, said fluid pressure actuated device being operatively connected to the said automatic and manual actuating means.

50 17. In a metal working machine a feed mechanism comprising a work carrier adapted to advance the work in the path of the machine and actuating means for said carrier comprising a feed shaft operatively connected to said carrier, a ratchet wheel securely mounted on said shaft and adapted to intermittently rotate the same, an arm mounted for angular movement on the hub of said wheel, a ratcheting pawl pivotally 55 mounted on said arm adjacent said wheel for engagement therewith, a mechanical linkage for operating said pawl and for effecting angular movement of said arm, a hand lever connected to said linkage, a second pawl mounted independently of said arm, 60 and means operative through the movement of said arm to effect engagement of said last mentioned pawl with the ratchet wheel to hold the latter in the position to which it is advanced by said ratcheting pawl. 70

18. In a metal working machine a feed mechanism comprising a work carrier adapted to advance the work in the path of the machine and actuating means for said carrier comprising a feed shaft operatively connected to said carrier, a ratchet wheel securely mounted on said shaft and adapted to intermittently rotate the same, an arm mounted for angular movement on the hub of said wheel, a ratcheting pawl pivotally 75 mounted on said arm adjacent said wheel for engagement therewith, a mechanical linkage for operating said pawl and for effecting angular movement of said arm, a hand lever connected to said linkage, a second pawl mounted independently of said arm, and means operative through the movement of said arm to effect engagement of said last mentioned pawl with the ratchet wheel to hold the latter in the position to which it is advanced by said ratcheting pawl. 80

85 19. In a metal working machine a feed mechanism comprising a work carrier adapted to advance the work in the path of the machine, actuating means for said carrier comprising a feed shaft operatively connected to said carrier, a ratchet mechanism securely mounted on said shaft and adapted to intermittently rotate the same, an arm mounted for angular movement on the hub of said wheel, a ratcheting pawl pivotally 90 mounted on said arm adjacent said wheel for engagement therewith, a mechanical linkage for operating said pawl and for effecting angular movement of said arm, a hand lever connected to said linkage, a second pawl mounted independently of said arm, and a fluid pressure actuated device operative through the movement of said arm to effect engagement of said last mentioned pawl with the ratchet wheel to hold the latter in the position to which it is advanced by said ratcheting pawl said fluid pressure device comprising a plunger adapted for engagement with said holding pawl, 95 a slide valve communicating with a source of fluid pressure and the atmosphere, and a mechanical linkage connecting said valve and the movable arm of said ratchet pawl to connect said plunger with the source of pressure. 100

105 20. A feed mechanism for metal working machines comprising a carrier for feeding work to be acted upon in the path of the machine, a feed shaft geared to said carrier and a ratcheting mechanism for automatically or manually rotating said shaft to advance said carrier, said ratcheting mechanism comprising a ratchet wheel mounted to rotate with said feed shaft, a pair of lever arms loosely mounted on the hubs of said wheel, a pawl mounted on each of said arms, and a stop pawl mounted independently of said arms, said pawls being adapted to engage the teeth of said wheel, means for automatically actuating one of said lever arms to rotate said feed shaft, and means for manually actuating the other of said arms to rotate said shaft, said last named means being independent of said automatic means. 110

115 21. A feed mechanism for metal working machines comprising a carrier for feeding work to be acted upon in the path of the machine, a feed shaft geared to said carrier and a ratcheting mechanism for automatically or manually rotating said shaft to advance said carrier, said ratcheting mechanism comprising a ratchet wheel mounted to rotate with said feed shaft, a pair of lever arms loosely mounted on the 120 hub of said wheel, a pawl mounted on each of said arms, and a stop pawl mounted independently of said arms, said pawls being adapted to engage the teeth of said wheel, means for automatically actuating one of said lever arms to rotate said feed shaft, and means for manually actuating the other of said arms to rotate said shaft, said last named means being independent of said automatic means. 125

hubs of said wheel, a pawl mounted on each of said arms, and a stop pawl mounted independently of said arms, said pawls being adapted to engage the teeth of said wheel, means for automatically actuating one of said lever arms to rotate said feed shaft, means for manually actuating the other of said arms to rotate said shaft, and independent means operative through both of said arm actuating means for effecting engagement of said stop pawl with said ratchet wheel.

21. A feed mechanism for metal working machines comprising a carrier for feeding work to be acted upon in the path of the machine, a feed shaft geared to said carrier and a ratcheting mechanism for automatically or manually rotating said shaft to advance said carrier, said ratcheting mecha-

nism comprising a ratchet wheel mounted to rotate with said feed shaft, a pair of lever arms loosely mounted on the hubs of said wheel, a pawl mounted on each of said arms, and a retaining pawl for said wheel, said pawls being adapted to engage the teeth of said wheel, a crank actuated rocker arm for actuating one of said lever arms, means associated with said frame for actuating said stop pawl, a manually operative linkage for actuating said other arm, and means associated with the manually actuated lever arm and independent of said rocker frame for actuating said stop pawl.

In testimony whereof, we hereunto sign our names.

LARS H. VOLD.

KARL R. HAMMERSTROM.
